UNITED STATES PATENT OFFICE.

JOHN E. BROWN, OF WASHINGTON COURT-HOUSE, OHIO, ASSIGNOR OF TWO-THIRDS TO PATRICK HAGERTY AND MICHAEL J. HAGERTY, OF SAME PLACE.

HEEL-BUILDING MACHINE.

SPECIFICATION forming part of Letters Patent No. 427,498, dated May 6, 1890.

Application filed September 21, 1889. Serial No. 324,600. (No model.)

To all whom it may concern:

Be it known that I, JOHN E. BROWN, a citizen of the United States, and a resident of Washington Court-House, in the county of 5 Fayette and State of Ohio, have invented certain new and useful Improvements in Heel-Building Machines, of which the following is a specification.

The object of my invention is to build a 10 shoe-heel, perforate the nail-holes, and nail the parts together ready to be put on a shoe by the ordinary shoe-heel machine.

Another object of my invention is to do 15 the several parts of the work by a single revolution of the operative shaft and to do the several steps of the work in consecutive time movements.

The various features will be fully set forth 20 in the description of the accompanying drawings, making a part of this specification, in which—

Figure 1 is a side elevation of my heel-building machine. Fig. 2 is a front end elevation. Fig. 3 is a top plan view of the table with that 25 part of the machine above the table removed. Fig. 4 is an opposite side elevation of Fig. 1. Fig. 5 is a central vertical section on line $y-y$, Fig. 4. Fig. 6 is a vertical section on a transverse line of Fig. 5. Fig. 7 is a cross-section 30 on line $x-x$, Fig. 5. Figs. 8 and 9 are detail views of the clutch. Fig. 10 is an enlarged sectional elevation of a nail-driver. Fig. 11 is a modified form of the toggle-joint.

1 represents the posts of the machine, and 35 2 the table. They are preferably cast integral, making a rigid frame.

3 represents the transmitting-shaft, which is driven by any ordinary power applied to the pulleys 4 and 5, 4 being an idler and 5 a loose pulley provided with clutch mechanism, so as to make it fast to the shaft, which will 40 be hereinafter explained.

6 represents the main working-shaft, which is driven by a spur-gear 7, meshing with the 45 spur-wheel 8. The shaft 6 carries an eccentric 9, which operates pitman 10, which is pierced to receive said eccentric, the upper end of which is provided with a slot 11, through which passes a stud 12. This stud 50 is rigidly connected to a rocking arm 13.

14 represents the journal of said rocking arm 13.

15 represents a plunger, which is loosely hooked to the rocking arm 13 and receives a compressing motion therefrom. Said plunger is journaled in overhanging bracket 16, which bracket is rigidly connected to the table. Said plunger is made in two parts, which are connected together by screw-threads $a-b$, for the purpose of adjusting the die 17 vertically, 55 by means of which the heel is shaped to the proper convexity by power applied to compress the lifts or layers. This die is preferably made detachable by a dovetail connection, as shown in Figs. 5 and 6, which allows 60 different-sized plungers to be applied and a renewal of the same.

c represents a spring keeper-pin, which fits in the groove in the thread a . The pitch of the threads is such that by turning the threaded sleeve one revolution a step adjustment is made, the spring-keeper c being removed for this purpose. The spring is simply for causing it to be re-engaged automatically in the groove. 70

The heel is formed in the female die 19. This die is preferably made with three offsets (more or less) $e-e'-e''$. This is for the purpose of saving material when making the heels smaller at the top than at the bottom 80 and bringing it nearer to the desired shape for trimming, enabling smaller pieces of leather to be used upon the heel than if a conical form of die were used, and also allowing the heel-pieces to be cut vertical and not 85 tapering. The die is detachably secured in position laterally by dovetail cleats 20. 21 represents the screw-bolts for holding the same in position. This die 19 is reciprocated at the appropriate time, as will be hereinafter explained. Underneath the die is placed a guide-block 22, through which is pierced a series of holes, (shown in Figs. 5 and 6,) through which pass the awls i . These awls are rigidly secured to the head-block 23, which 90 is detachably secured to the guide-block 25, and is made detachable from the guide-block, so that it may be changed for different-sized heels. The guide-block 25 moves in a boss 24 on the table 2, and is swiveled to the sleeve 95 100

27, which is screw-threaded in the collar 26. Said collar 26 is rigidly connected by arms 28 to the wrist-block 29.

30 represents a wrist-pin for a hinge-connection to the rocking arm 31. Said rocking arm is journaled to the pendent arm 32 by a pin 33, and it is operated by a connecting-rod 34, attached to the crank-pin on the projecting arm of pitman 10, which imparts vertical motion to the plunger-frame A, which frame is composed of parts 25 26 27 28, above described.

In the space between the series of awls *i* is a nail-driver *o*, which is employed to drive a nail through the center of the heel simultaneously with the operation of the awls in perforating the heel-holes. Said nail attaches the several pieces of heel together. The said nail-driver *o* is preferably made of three sections *o' o'' o'''*, which are journaled in the sleeve B, which is made of suitable shape to receive said sections of the nail-driver, which are progressively smaller from the bottom up, as shown in Fig. 10. The nail to be driven is dropped into the central orifice. It is essential that this orifice shall be but slightly larger than the nail, so as to hold it in vertical position and prevent it from bending, and the nail-driver must be small enough to follow it through this orifice and drive the nail through the heel, and by making the nail-driver of sections progressively larger below the nail-driving portions it strengthens and supports the nail-driving mechanism and renders it much less liable to bend than if the nail-driver were made as small as the nail. It will be observed that the nail-driver *o* and the awls *i* are both supported upon and driven by the same plunger-frame A and work simultaneously.

In order to adjust the series of awls to any given depth and perforation they are supported upon a screw-threaded adjusting-sleeve 27, which may be turned without affecting the position of the nail-driving spindle *o'''*. This spindle is also screw-threaded at its lower end and connected to the adjusting-nut 37.

38 represents a jam-nut above the adjusting-nut for setting the parts in an adjusted position; hence, the nail-driver may be adjusted to any suitable depth of heel without affecting the awl adjustment, and vice versa. It is desirable to drive the nail clear through the heel and clinch it slightly against the die 17, which secures the several pieces together, while the circular series of nail-holes need not be pierced through.

In order to adjust the length of the stroke for any given nail and corresponding perforations to correspond with the depth of the heel, the connecting-rod 34 is adjustably connected to the rocking arm 31 by the following instrumentalities: 39 represents a screw-rod 55 tapping through the bottom of said rocking arm 31. 40 represents a slot, in which the journal-pin 41 moves. 42 represents a slot

in the end of the connecting-rod. The screw-rod 39 is provided with a head which swivels in the journal-block which fits and moves in said slot 40. As the screw 39 is turned the connecting-rod 34 is raised or lowered, the journal-block moving in the slot 40 and the journal 41 in the slot 42, whereby the length of the stroke of the frame A is governed by the position of the link or rod 34. 43 represents an index-finger for indicating the adjustment of the stroke.

It will be observed that the series of awls *i* are fastened to and detached with the head 80 or carrying block and a different size can be employed, and that the stroke of the awls or nail-driver may be varied at pleasure. The pressure is imparted to the heel to shape it by means of the pitman 10 and the rock- 85 ing arm 13. This pressure I prefer to retain sufficiently long to drive the nail and perforate the awl-holes. I also desire to make one heel with one revolution of the work-shaft 6. Hence a portion of the time the 90 pressure is employed for forming the heel, and the pressure is retained for a portion of the time for driving the nails and perforating nail-holes. During a part of a revolution the die 17 is stationary. This is accomplished 95 by means of the slot 11 of rock arm 13, and to maintain the pressure I provide a toggle-joint lever 44, one end of which is connected to the rocking arm 13 and the other to the table 2. This toggle-joint is straightened by 100 the downward movement of arm 13, operating the plunger and die, in the position shown in dotted lines, Fig. 1. When the work has been completed, in order to lift the arm I provide 105 a trip to open the toggle and allow the plunger to be raised, which is accomplished by means of the boss 45, formed on the pitman 10. The said pitman, descending, strikes against the boss 46, formed on the toggle-joint, knocks 110 it out, and allows the piston to be raised after the nail has been driven and the nail-holes perforated. As constructed the rock-arm 13 drops by gravity.

In order to prevent shock to the arms and take off strain from the pin, I provide a stop 115 47, upon which the rock-arm 13 rests normally, the upward motion being imparted by the eccentric 9, and the free downward movement of the arm by gravity, or the upper end of slot in pitman 10 if gravity fails.

In order that the machine may automatically stop itself, I provide a clutch mechanism. In Fig. 9 I have shown a diagram of the clutch mechanism, in which 49 represents the hub of the pulley 5, and 50 represents the 125 disk keyed to the shaft, as shown in sections, Fig. 8. 51 represents a circular head in said disk; 52, a lock-pin, which is provided with an inclined notch, through which passes an inclined arm 53. When the arm 53 is pulled 130 down, the pin 52 is drawn out of engagement with the notch 54 of hub 49, and when the arm is raised the pin 52 is shot back to lock the pulley 5 to the disk 50. 55 represents a coil-

spring placed in the groove 56, one arm of which is attached to said disk and the other arm attached to the trip-arm 53. This arm is dropped by means of pin 56, which pin 5 journals in the box 57, attached to the frame. The outer end of said pin 56 is provided with a lug or pin engaging with the fork end of the lever 58. Said lever 58 is journaled upon the frame and is provided with fork 59, in 10 which engages the horizontal arm 60, one end of which is pivoted to the frame and the other end to connecting-rod 61. Said connecting-rod is pivoted in its outer end to the die 19. This die 19 is reciprocated by hand to engage 15 the clutch. This die 19 is pulled forward by the operation of the machine into the position shown in Fig. 4, so as to be in front of the plunger 17, as shown in Fig. 4, so that the operator may place the piece forming the heel 20 into the offset of the die. When the pieces have all been laid in, he pushes this die back, which, by means of the connecting-rod 61, arm 60, and forked lever 58, disengages pin 56, releasing it from engagement with the lug 63 on 25 the shaft-arm 53. The recoil of the spring 55 drives the arm 53, which drives the pin 52 into position for engaging the clutch and starting the machine. At the end of the revolution it is stopped by means of the arm 64, which 30 is provided with latch 65, which is hit by the lug 66, placed on one of the arms of the spur-wheel 8. The striking said lug against the latch 65 throws the arm 64 outward. The upper end of said arm is provided with a fork 35 67, which engages with the shaft-arm 60 and thrusts the die 19 and the heel forward into position shown in Fig. 4.

In order that the heel or die 19 may be retained in the forward position, I provide a catch 68, which projects up through the table, engaging with the notch in the bottom of die 19, as shown in Figs. 1 and 4. To disengage this connection, I provide connecting-rods 69 and lever 70, which are operated by hand to draw the catch down and allow the die to be pushed back when the operator is ready to start the machine.

In order to remove the heel from the die, I provide the following instrumentalities: 71 represents a spring-treadle; 72, a connecting-rod operated by said spring-treadle and engaging with the rocking arm 73 and pivoted to the under side of the table. The inner end of said rocking arm is provided with plunger 74, which passes up through the table into the bottom of the die 19, when it is in its forward position, as shown in Fig. 4. The pressure of said plunger striking against the under side of the heel within the die loosens the heel up and allows it to be readily taken out.

In Fig. 11 I have shown a substitute for the toggle-joint, which is a locking mechanism and composed substantially of the pillar E, attached to the table of the machine. F represents a locking-arm hinged to the rocking arm 13. The end of the pillar E and arm F are notched. As the forward end of the rock-

ing arm descends the arm F is drawn up until the notch therein engages with the notch of the pillar E, thereby locking the rocking arm 13 in position. The arm F is provided with boss 46, which the boss 45 on the pitman 10 strikes, thereby unlocking it, operating in the same manner as a toggle-joint; but the device here shown is more positive than a toggle-joint. G represents a spring attached to the arm 13 and bearing against the arm F, so as to secure its engagement with the pillar E. This is the equivalent of the "toggle-joint" as embraced by said term.

The operation of my machine is as follows: The parts are adjusted so that the die 19 is in the position in Fig. 4 at the end of the revolution. The clutch is out of engagement, and the pulley 5 is running as an idler. The operator fills the die 19 with appropriate-sized pieces for forming the heel. The nail is dropped through the hole C, pierced through the arm 61, which hole is vertically over the orifice containing the nail-driver o. When 90 the pieces have been laid in, the operator releases the catch 68 by means of the hand-lever 70 and pushes the die 19 back into the position shown in Fig. 1, which motion operates the clutch mechanism before described, making 95 the pulley 5 fast to the disk 50, thereby imparting motion to the working-shaft 6, which lifts the pitman 10, operating the rocking arm 13 and pushing the plunger 15 down. This brings the toggle-joint 44 into a vertical 100 position and locks the arm 13 in position. The pitman then has reached the end of its stroke and commences to travel down, imparting motion through the connecting-rod 34 to the rocking arm 31, which rocking arm, 105 as before described, operates the awls and nail-driver. The compressing-die 17 holds the heel under compression and the nail is clinched by coming in contact with said compressing-die.

In order to prevent the awls and nail-driver from being operated until after the compression is applied to the heel, the slot 42 causes it to work as an idler until that pressure has been applied. When the said connecting-rod 115 has traveled the length of said slot 42, it engages with the pin 41, and during the remaining portion of its forward movement operates the frame A, as before described. As soon as the boss 45 has traveled downward it comes in 120 contact with the boss 46, drops the toggle 44, and allows the rocking arm 13 to be dropped down. The pin or lug 66 on the frame of the spur-wheel 8 trips the clutch and throws the die 19 forward at the end of the stroke, when 125 the machine is ready for a second operation.

A shoe-heel may be made in this machine without the nail mechanism by using an adhesive substance securing the pieces of the heel temporarily together, so that it may be attached to the boot or shoe by nailing, and dispense with the nail-driving mechanism; but the preferred form is to employ that, as the attachment is more secure.

The nail-driver may be adjusted so as to drive a nail through the heel and have it clinch up against the compressing-die, which is the preferred form of operation.

5 Having described my invention, what I claim is—

1. In a heel-building machine, the combination of a female shaping-die, a movable compressing male die, a reciprocating plunger-frame having a series of awls, a tubular guide in the plunger-frame, a nail-driver moving in the tubular guide, and means for operating the compressing-die and moving the plunger-frame to simultaneously advance the nail-driver and the awls to drive a nail as the heel

15 is pierced by the awls, while the wheel is held under compression by the male die, and which male die acts to clinch the nail, substantially as described.

2. In a heel-building machine, the combination of a female shaping-die, a male compressing-die, a plunger-frame having a series of awls and a tubular guide B, having different internal diameters, a nail-driver moving 25 in the guides and having a series of offsets conforming to and fitting the internal diameters thereof for driving a nail as the awls pierce the heel, and means for operating the male die and the plunger-frame to simultaneously advance the awls and nail-driver for piercing the heel and driving a nail while the said heel is held under compression by the compressing-die, substantially as described.

3. In a heel-building machine, the combination, with a female shaping-die and a male compressing-die, of a plunger-frame comprising a head-block provided with a series of awls, a tubular guide passing through the head-block, a nail-driver located in the guide 40 and operating within the space between the awls to drive a nail as the awls pierce the heel, and means for operating the plunger-frame to simultaneously advance the awls and nail-driver, substantially as described.

4. In a heel-building machine, the combination, with a table, a female shaping-die, and a male compressing-die, of a plunger-frame having a guide-block 25, a head-block 23, detachably seated in said guide-block and provided with a series of awls, a tubular guide B, extending through the guide and head blocks, a nail-driver located in the guide and operating in the space between the awls to drive a nail as the awls pierce the heel, and 55 means for operating the male die and the plunger-frame to simultaneously advance the awls and nail-driver and pierce the heel and drive a nail while the said heel is held under compression by the compressing-die, substantially as described.

5. In a heel-building machine, the combination, with a female shaping-die and a male compressing-die, of a plunger-frame, comprising a lengthwise-adjustable sleeve 27, supporting a head-block which carries a series of awls, a tubular guide B, extending through the sleeve and head-block, a lengthwise-adjustable nail-driver o, arranged in the tubular guide and operating in the space between the awls, and means for operating the male die, 70 and the plunger-frame to simultaneously advance the awls and the nail-driver and pierce the heel and drive a nail while the said heel is held under compression by the compressing-die, substantially as described.

justable nail-driver o, arranged in the tubular guide and operating in the space between the awls, and means for operating the male die 70 and the plunger-frame to simultaneously advance the awls and the nail-driver and pierce the heel and drive a nail while the said heel is held under compression by the compressing-die, substantially as described.

6. In a heel-building machine, the combination, with a female shaping-die and a male compressing-die, of a plunger-frame A, comprising a lengthwise-adjustable sleeve 27, supporting a head-block which carries a series 80 of awls, a tubular guide B, extending through the sleeve and head-block, a lengthwise-adjustable nail-driver o, arranged in the tubular guide and operating in the space between the awls, an oscillating arm 31, connected 85 with the plunger-frame, and means for oscillating said arm and operating the male die, substantially as described.

7. In a heel-building machine, the combination of a female shaping-die, a male compressing-die, a plunger-frame comprising a sleeve 27, supporting a head-block which carries a series of awls, a tubular guide B, extending through the sleeve and head-block, a nail-driver o, arranged in the tubular guide 95 and operating in the space between the awls and oscillating arm 31, connected with the plunger, a rocking arm 13, which acts on the male die, a pitman 10, connected with the said oscillating and rocking arms, and means for reciprocating the pitman, substantially as described.

8. In a heel-building machine, the reciprocating female shaping-die 19 and the compressing-die 17, operated by a rocking arm 13, 105 driven by the main shaft, in combination with clutch mechanism which is brought into engagement by the rectilinear reciprocation of the female shaping-die 19, substantially as specified.

9. In a heel-building machine having the compressor-die 17, the supporting-die 19, automatically operated by the arms 61 and 64, and the tripping mechanism, whereby said die is thrown forward at the end of a revolution, 115 substantially as described.

10. In a heel-building machine, the combination of clutch mechanism and mechanism operated by a reciprocation of die 19 for engaging the clutch and setting the machine in motion, and the tripping devices operated by the driving mechanism for releasing the clutch and reciprocating the die 19 forward at the end of a revolution, substantially as herein specified.

11. In a heel-building machine having the supporting-die 19 and the plunger-die 17, the latter operated by the pitman 10, connected to the rocking arm 13, the toggle-joint 44, for locking the plunger down during a portion of 130 the revolution, substantially as specified.

12. In a heel-building machine, the combination, with a table, a female shaping-die 19, and a male compressing-die 17, of a rocking

- arm 13, acting at one end on the male die, a pitman 10, connecting with the rocking arm and having a trip 45, means for reciprocating the pitman, and the toggle-lever 44, connected 5 with the table and the rocking-arm for temporarily locking the male die down, said toggle-lever being released by the trip to permit the male die to ascend, substantially as described.
- 10 13. In a heel-building machine, the combination of a female shaping-die, a male compressing-die, a plunger-frame comprising a head-block carrying a series of awls, a stationary tubular guide extending through said 15 head-block, a nail-driver movable in the tubular guide and operating to drive a nail in the space between the awls, and means for operating the plunger-frame and simultaneously advancing the awls and the nail-driver to
- drive a nail as the awls pierce the heels, substantially as described.
14. In a heel-building machine, the combination, with a female shaping-die and a male compressing-die, of a plunger-frame carrying awls, an oscillating arm 31, connected with 25 the plunger-frame and having the slot 40, the link 34, having a slot 42, and a pin 41, extending through the slot in the oscillating arm, and the screw 39, for adjusting the said pin vertically in the slot of the oscillating 30 arm, substantially as described.

In testimony whereof I have hereunto set my hand.

JOHN E. BROWN.
